(Continued)*Primary Examiner* — George D. Kirschbaum*Assistant Examiner* — Jennifer L Watkins(74) *Attorney, Agent, or Firm* — McDermott Will & Emery LLP(57) **CLAIM**

I claim the ornamental design for a medical device for wound care, as shown and described.

DESCRIPTION

FIG. 1 is a top perspective view of a medical device for wound care according to the new design;

FIG. 2 is a bottom perspective view of the medical device for wound care shown in FIG. 1;

FIG. 3 is a left side view of the medical device for wound care shown in FIG. 1;

FIG. 4 is a right side view of the medical device for wound care shown in FIG. 1;

FIG. 5 is a top view of the medical device for wound care shown in FIG. 1;

FIG. 6 is a bottom view of the medical device for wound care shown in FIG. 1;

FIG. 7 is a front view of the medical device for wound care shown in FIG. 1; and,

FIG. 8 is a rear view of the medical device for wound care shown in FIG. 1.

The broken lines in the drawings are for the purpose of illustrating portions of the article and form no part of the claim.
